UNITED STATES PATENT OFFICE

VINCENT F. SLEZAK, OF NEW YORK, N. Y., ASSIGNOR TO INTERNATIONAL TICKET SCALE CORPORATION, OF NEW YORK, N. Y., A CORPORATION OF DELAWARE

DESIGN FOR A COIN-CONTROLLED SCALE

Application filed November 19, 1930. Serial No. 37,709. Term of patent 3½ years.

To all whom it may concern:

Be it known that I, VINCENT F. SLEZAK, a citizen of Czechoslovakia, residing at New York city, New York, have invented a new, original, and ornamental Design for a Coin-Controlled Scale, of which the following is the specification, reference being had to accompanying drawings, forming part hereof.

In the drawings—

Fig. 1 represents a perspective view of the

coin-controlled scale, showing my new design; and

Fig. 2 is a cross-sectional view taken about midway of Fig. 1 illustrating the panel effect.

I claim:

The ornamental design for a coin-controlled scale substantially as shown.

In testimony whereof, I affix my signature.

VINCENT F. SLEZAK.
